UNITED STATES PATENT OFFICE.

ROBERT G. RATE, OF IOWA CITY, IOWA.

HUSKING-MITTEN.

SPECIFICATION forming part of Letters Patent No. 688,117, dated December 3, 1901.

Application filed January 28, 1901. Serial No. 45,094. (No model.)

To all whom it may concern:

Be it known that I, ROBERT G. RATE, a citizen of the United States, residing at Iowa City, in the county of Johnson and State of Iowa, 5 have invented a new and useful Husking-Mitten, of which the following is a specification.

This invention relates to a novel husking-mitten, having attached to the palm thereof a husking-pin designed to be utilized in husking corn or for similar purposes.

The primary object of the invention is to prevent the husking-pin from slipping in either direction or from rolling out of position without employing retaining means 15 which will unduly constrict or cramp the hand of the user. This end is attained by securing the pin upon a mitten through the medium of securing means which passes through the mitten and between the fingers to prevent 20 the objectionable movement of the pin.

Another object of the invention is to attach the husking-pin to the mitten in a novel manner, so as to prevent tearing of the material at the points of connection, and to 25 incorporate in the structure a shield and a grip-strap related in a manner to permit the device to be adjusted securely upon the hand of the user to facilitate the gripping of the pin and to prevent it from slipping longitudinally when in use. The desired end is accomplished by means of the construction and 30 arrangement of parts to be fully described, illustrated in the accompanying drawings, and defined in the appended claims.

35 In said drawings, Figure 1 is a front elevation of the mitten. Fig. 2 is a rear elevation thereof. Fig. 3 is a transverse section on the line 3-3 of Fig. 1. Figs. 4, 5, and 6 are front and rear elevations and a transverse sectional view, respectively, of a modified arrangement of the pin-securing means. Figs. 7, 8, and 9 are a similar group of another modification, and Figs. 10, 11, and 12 are illustrations of a still further variation of the arrangement of parts.

Referring to the numerals employed to designate corresponding parts through the views, 1 indicates a mitten which may be of any desired form and construction, but preferably 50 embodies leather or other durable facings 2 and 3 for the palm and thumb, respectively, the former extending by preference to the

outer end of the mitten. The thumb is additionally protected by a reinforcing piece or shield 4, and the index-finger is likewise additionally protected by a finger-shield 5. The shield 5 may be of any desired form and material, but I employ a circular piece of leather, as shown, folded around the edge of the mitten and secured to the facing 2, as by a rivet 6, which serves additionally as a securing device for the husking-pin 7, extending transversely across the front of the mitten and having its curved point or beak extended sufficiently beyond the shield 5 to permit of 65 its use as a ripper in the ordinary manner. At its end opposite the beak the pin 7 is secured to the facing 2, as by a rivet 8, which also secures the ends 9 of the buckle-retaining loop 10 of the buckle 11. The pin is 70 thus securely fastened to the mitten, which is reinforced at the points of connection by the shield 5 and the loop 10, respectively. We now have a mitten equipped with a permanently-attached husking-pin and with a 75 shield properly disposed to protect the index-finger and thumb of the wearer during the husking; but unless additional provision is made the pin is likely to move to an objectionable extent during its use unless the mitten happens to fit accurately upon the hand 80 of the user. I therefore rivet or otherwise connect one end of the grip-strap 12 with the pin 7 at its middle. This strap is then passed through slits 13 and 14 in the front and back 85 of the mitten, and after being slidably connected to the end of the shield-strap 15, extending from the rear edge of the shield 5, is carried around the edge of the mitten and is 90 adjustably secured to the rear end of the pin 7 by means of the buckle 11. The slideable connection between the pad-strap 15 and the grip-strap 12 may be varied within wide limits; but I prefer to provide the former with three slits 16, 17, and 18, through which the 95 strap 12 is passed alternately in opposite directions, as shown. It will now be observed that not only is the pin permanently connected to the facing of the mitten adjacent to the opposite edges thereof, but that it is also retained by the grip-strap 12, connected to the pin at its center and passing through the mitten at a point which will divide the mitten into two-finger compartments. Thus when 100

the mitten is drawn upon the hand of the user the grip-strap will pass between the second and third fingers and will constitute a fastening device absolutely precluding the possibility of endwise slipping of the pin after the grip-strap has been drawn up to fit snugly around the third and fourth fingers.

5 The sliding connection between the pad-strap 15 and the grip-strap 12 will obviously permit any necessary adjustment of the latter and will at the same time cause the pad 5 to be drawn smoothly around the index-finger to prevent possible interference in the manipulation of the pin.

15 Attention is directed particularly to the fact that the grip-strap does not pass around all of the fingers, but is constricted upon the third and fourth fingers only, so that the first and second fingers are left free for such movement as is desirable and necessary for the proper manipulation of the beak end of the husking-pin. It is in view of this requirement that the shield 5 is not permanently connected to the back of the mitten, but is simply retained by means of the shield-strap 15, having sliding connections with the grip-strap 12, so that the first and second fingers will not be unduly constricted.

30 The essential novelty underlying the invention is the attachment of the pin to a mitten and its retention during use by means which pass through the mitten and between the fingers, whether such means is the grip-strap, as shown, or some part associated therewith.

35 In the first three figures of the drawings I have shown, as stated, a grip-strap secured to the pin and passed through the mitten for engagement with a strap-retaining device or buckle secured in place by the rivet 8, which retains the rear end of the pin.

40 In the form shown in Figs. 4, 5, and 6 the buckle-retaining loop 10 is secured by a separate rivet 8^a, disposed beyond the end of the pin, so that while the strap-retaining device is disposed adjacent to the end of the pin it is not connected thereto.

45 In the form shown in Figs. 7, 8, and 9 the buckle-retaining loop 10, instead of being secured to the mitten adjacent to the fourth finger, is secured to the pin at its middle and passes through the mitten for attachment to the grip-strap, which in this instance is secured at one end by the rivet 8^b, which secures the pin, although obviously the grip-strap might be secured by a separate rivet, as in the case of the loop 10 in Fig. 6.

50 In Figs. 10, 11, and 12 the buckle is entirely omitted and the grip-strap is permanently secured at its opposite ends by rivets, as shown.

60 In the claims I shall refer to "means for retaining the pin against displacement upon the hand when in use" and to a "grip device," by which terms or expressions I desire to be understood as meaning the grip-strap, as shown in Fig. 12, or the grip-strap and associated retaining devices, irrespective of

whether the strap itself passes through the mitten or whether the buckle, buckle-loop, or other associated element is utilized for this purpose.

70 From the foregoing it will be observed that I have produced a simple and ingenious husking-mitten; but while the present embodiment of the invention is believed at this time to be preferable I wish to reserve the right to effect such changes, modifications, and variations thereof as may be properly embraced within the scope of the protection prayed.

75 What I claim is—

1. A husking-mitten provided with a husking-pin, and a fastening device for retaining the pin against displacement upon the hand when in use, said device being passed through the mitten from front to back for disposal between the fingers.

80 2. A husking-mitten provided with a husking-pin and having a grip-strap permanently secured to the middle of the mitten-front and passed through said mitten from front to back for disposal between the fingers, and means upon the exterior of the mitten for detachably retaining the grip-strap.

85 3. A husking-mitten provided with a husking-pin disposed across its front, a strap-retaining device, and a grip-strap passed through the mitten from front to back for disposal between the fingers and connected to the strap-retaining means.

90 4. A husking-mitten provided with a husking-pin disposed across its front, a strap retaining and adjusting device, and a grip-strap secured to the pin and passed through the mitten from front to back for disposal between the fingers, said grip-strap being disposed for retention and adjustment by the strap retaining and adjusting device.

100 5. A husking-mitten provided with a husking-pin disposed across its front, a strap-retaining device disposed upon the exterior of the mitten at or adjacent to one end of the pin, and a grip-strap secured to the pin intermediate of the ends of the latter and passed through the mitten from front to back for disposal between the fingers and for connection with said strap-retaining device.

115 6. A husking-mitten provided with a husking-pin disposed across its front, and having a buckle at one end, and a grip-strap secured to the pin and passed through the mitten for adjustable connection with the buckle.

120 7. A husking-mitten provided with a husking-pin disposed across its front side and having a buckle at one end, a grip-strap secured to the pin and passed through the mitten, approximately at the middle line thereof, and designed to be passed around the edge of the mitten for adjustable connection with the buckle, and a shield disposed at one edge of the mitten and retained by the grip-strap.

125 8. A husking-mitten provided with a husking-pin extending across its front and provided at its opposite ends respectively with

a beak and a buckle, a grip-strap passed entirely through the mitten and connected at one end to the pin, and a shield disposed at one edge of the mitten adjacent to the beak 5 of the pin, and having sliding connection with the grip-strap.

9. A husking-mitten provided with a husking-pin across its front side, a beak and buckle disposed respectively at opposite ends of the 10 pin, a grip-strap connected at one end to the middle of the pin, and passing through the mitten to the rear side thereof and adapted for adjustable connection to the buckle, a shield folded around the front edge of the 15 mitten adjacent to the beak of the pin, and a shield-strap connected at one end to the shield, and having sliding connection at its opposite end to the grip-strap.

10. A husking-mitten having a husking-pin 20 secured across the front face thereof, a shield and a buckle-retaining loop disposed under the opposite ends of the pin, securing means for the loop and shield, said means serving additionally to retain the pin, a buckle retained by the loop, a grip-strap connected to the pin at its center and passed entirely through the mitten for adjustable connection 25 with the buckle, a shield-strap connected to the shield at the rear side of the mitten,

and a slidable connection between the shield- 30 strap and grip-strap.

11. The combination with a husking-pin having a beak at one end and strap-engaging means at its opposite end, of a grip-strap secured at one end to the husking-pin, approximately at the middle thereof, and disposed for adjustable connection with the strap-engaging means, a shield secured to the pin adjacent to its beak, and a shield-strap extending from the shield and having connection 40 with the grip-strap.

12. The combination with a husking-pin having a beak at one end and strap-engaging means at its opposite end, of a grip-strap secured at one end to the husking-pin, approximately at the middle thereof, and disposed for adjustable connection with the strap-engaging means, a shield secured to the pin adjacent to its beak, and a shield-strap extending from the shield and having sliding connection 45 with the grip-strap.

In testimony that I claim the foregoing as my own I have hereto affixed my signature in the presence of two witnesses.
